(57) **CLAIM**

The ornamental design for a dog training device, as shown and described.

DESCRIPTION

FIG. 1 is a perspective angled front view of the dog training device, which embodies my design;
FIG. 2 is a top view thereof;
FIG. 3 is a bottom side view thereof;
FIG. 4 is a front side view thereof;
FIG. 5 is a rear side view thereof;
FIG. 6 is a left side view thereof; and,
FIG. 7 is a right side view thereof.
